(57) **CLAIM**

The ornamental design for a container lid as shown and described.

DESCRIPTION

This application is also related to U.S. application Ser. No. 18/450,668, filed Aug. 16, 2023 the entire disclosures of which are hereby incorporated herein by reference.

FIG. 1 is a perspective view of a container lid showing my new design according to an embodiment;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is another perspective view thereof, in a state of use; and,

FIG. 9 is another front view thereof, in a state of use.

The dashed lines in the drawings depict portions of the container lid that form no part of the claimed design. The remaining dashed lines in FIGS. 8-9 in the form of a container body depict environmental subject matter and form no part of the claimed design. The dash-dot lines in FIGS. 1, 6, and 8 depict the bounds of the claimed design and form no part thereof.

1 Claim, 7 Drawing Sheets

Related U.S. Application Data

which is a continuation-in-part of application No. 29/784,376, filed on May 19, 2021, now Pat. No. Des. 1,023,762, which is a continuation of application No. 29/771,082, filed on Feb. 19, 2021, now Pat. No. Des. 1,010,448, which is a continuation of application No. 29/740,976, filed on Jul. 8, 2020, now Pat. No. Des. 911,179, said application No. 29/784,376 is a continuation of application No. 16/598,443, filed on Oct. 10, 2019, now Pat. No. 11,484,152, said application No. 29/740,976 is a continuation of application No. 29/708,953, filed on Oct. 10, 2019, now Pat. No. Des. 911,843, said application No. 29/771,082 is a continuation of application No. 16/598,443, filed on Oct. 10, 2019, now Pat. No. 11,484,152.
